Primary Examiner—Alan P. Douglas*Assistant Examiner*—Rosemary K. Tarcza(74) *Attorney, Agent, or Firm*—Wolf Greenfield & Sacks(57) **CLAIM**

The ornamental design for a surge protector, as shown and described.

DESCRIPTION

FIG. 1 is a side, top, perspective view of the surge protector with elements thereof and thereon shown in phantom;

FIG. 2 is a front view thereof;

FIG. 3 is a rear view thereof;

FIG. 4 is a left side view thereof;

FIG. 5 is a right side view thereof;

FIG. 6 is a top view thereof; and

FIG. 7 is a bottom view thereof; and,

FIG. 8 is a side, top, perspective view thereof in an extended position.

The broken lines are for illustrative purposes only and form no part of the claimed design.
